HEELED SHOE.
FILED MAY 29, 1922.

15-¹² Inventor:
James F. Marshall
^{14²} by right down Linley, May,
Atlys

UNITED STATES PATENT OFFICE.

JAMES F. MARSHALL, OF SWAMPSMOTT, MASSACHUSETTS.

HEELED SHOE.

Application filed May 29, 1922. Serial No. 564,203.

To all whom it may concern:

Be it known that I, JAMES F. MARSHALL, a citizen of the United States, residing at Swampscott, in the county of Essex and 5 State of Massachusetts, have invented new and useful Improvements in Heeled Shoes, of which the following is a specification.

This invention relates to a shoe having a heel, the breast of which forms one side of 10 a space between the tread faces of the heel and the outer sole, the word "shoe" being intended to apply to any article of foot-wear thus characterized.

The object of the invention is to provide 15 a shoe, the heel of which is forwardly extended at its breast end to adequately support that portion of the bottom of the foot located under the forward portion of the bone known as the oscalsis or calcaneum, 20 without imparting to the heel an undesirably clumsy and bulky appearance, so that the aspect of the heel does not differ materially from that of a standard heel, the breast of which is not forwardly extended.

25 The invention is embodied in the improvements hereinafter described and claimed.

Of the accompanying drawings forming a part of this specification,—

30 Figure 1 is a side view of a shoe embodying the invention, showing by dotted lines a side view of the skeleton of a human foot within the shoe.

Figure 2 is a bottom view of the shoe.

35 Figure 3 is a perspective view of the heel shown by Figures 1 and 2, as it would appear if severed on the line 3—3 of Figure 1.

Figure 4 is a view indicating by shade lines, the portions of the bottom of a human 40 foot constituting the actual tread, and by dotted lines, the pressure-supporting area of the heel shown by Figures 1, 2 and 3.

Figure 5 is a bottom view, showing the preferred form and proportions of the top 45 lift of the heel.

Figures 6 and 7 are views similar to Figure 5, showing modified forms.

The same reference characters indicate the same parts in all of the figures.

50 When the weight of the body is supported by the foot, the portions of the foot bottom that are subjected to pressure against the inner sole of a shoe, and collectively constitute the foot tread, have the form indicated by shade lines in Figure 4.

The portion of the tread within the dot-

ted line designated by the numerals 12, 14 and 15 (Figure 4), (these numerals designating portions of the shoe heel), is the portion directly under the oscalsis or calcaneum 60 *o*, and under a portion of the astragalus *a*. The downwardly facing surface of the oscalsis has at its forward portion a contour conforming approximately to the dotted lines 14, 14. The calcaneum is at the rear 65 end of the arch of the foot, and its forward portion projects forward from the breast of the shoe heel as ordinarily formed, and considerably overhangs the breast of an ordinary heel, the proportions of which are 70 dictated by custom, and are such that the breast is so far behind the forward portion of the bones above named, that the forward portion of the heel does not adequately support these bones.

The ends of the breast are usually on a line at right angles with the median line *b*, *b*, the breast being either straight, or having a reentrant curvature between said ends.

In a heel conforming to the dictates of custom or fashion, the ends of the breast are so spaced from the median line of the back of the heel, that the curved margin of the heel does not project forward to such 85 an extent as to impart an objectionably elongated appearance to the heel.

In carrying out my invention, I provide a shoe with a heel which, in effect, conforms to the dictates of custom or fashion, and affords an adequate support for the forward portion of the bones above named, at the median line of the shoe. The curved margin 12 of the heel is of minimum length, from end to end of the breast. By this, I mean 90 that the forward projection of the ends of the curved margin from the median line of the back of the heel is practically the same as in a standard heel, so that said margin when viewed from either side, is not objectionably elongated. The ends 15 of the breast are substantially in alinement with each other, on a line at right angles with the median line, so that they are abreast of each other, neither projecting forward 100 of the other.

The breast is salient and has a forwardly projecting crown or apex 13, located midway between its ends and extending substantially perpendicular to the tread face of the top 110 lift. The crown is preferably formed by the intersection of two oblique faces 14, said

intersection forming an obtuse angle at 13, although the breast may have a curved crown 13^a, as shown by Figure 6. The crown may be formed by the intersection of 5 two concave faces 14^a, as shown at 13^b, Figure 7.

It will now be seen that the breast formed as described, provides an extension of the heel, adapted to conform approximately to 10 that portion of the bottom of the foot which is under the forward portion of the oscalsis, and under a considerable portion of the astragalus, and that the heel having said extension is formed to more adequately support 15 the said bones at the median line of the tread, than an ordinary standard heel, as may be seen by the dotted lines 20 and 21, (Figure 1). The line 20 is an extension of the crown 13, and the line 21 is an extension 20 of the central portion of the breast of an ordinary heel. If the breast is concave, as is usually the case, the line 21 will be more widely separated from the line 20, and nearer the rear end of the heel.

25 The form of the breast is such that the said extension has a limited visibility. I mean by this, first, that when the shoe is viewed from either side, in the direction of the arrow *x* (Figure 4), the breast, while 30 visible, is in the shadow of the shank portion of the outer sole, as indicated by Figure 1, so that it is not objectionably conspicuous; and secondly, when the shoe is viewed obliquely in the direction of either of the arrows *y* and *z*, the apparent length of the 35 heel is not greater than the distance between

the rear end of the heel and the breast ends 15, the breast being invisible when viewed in the direction of the arrow *y*.

The said extension enables the heel to be 40 united to the outer sole by a fastener 18, inserted in the inner and outer soles, the usual shank stiffener between said soles, and the extension forward of the ends of the breast, as indicated by dotted lines in Figures 45 1 and 2, said fastener supplementing the usual heel-attaching nails, and increasing the strength of the connection between the heel and the bottom of the shoe.

The heel may be provided with a cushioning 50 top lift of rubber or other material, having a breast of the form described.

I claim:

A shoe having a heel, the curved margin of which is of substantially the length of a 55 standard heel, the breast ends being substantially in alignment with each other on a line at right angles with the median line of the shoe and considerably in rear of the portion of the innersole which comes beneath the 60 forward end of the oscalsis of the wearer's foot, and having a forwardly projecting crown extending from the ends of the breast to said median line and under that part of the wearer's foot which is beneath the forward portion of the oscalsis, said extension being adapted to support said portion of the 65 foot at the median line of the tread and having a limited lateral visibility.

In testimony whereof I have affixed my 70 signature.

JAMES F. MARSHALL.
